UNITED STATES PATENT OFFICE.

CRAIG D. MUNSON, OF WALLINGFORD, CONNECTICUT, ASSIGNOR TO INTERNATIONAL SILVER COMPANY, OF MERIDEN, CONNECTICUT, A CORPORATION OF NEW JERSEY.

DESIGN FOR A DOLL OR SIMILAR ARTICLE.

Application filed March 24, 1925. Serial No. 12,868. Term of patent 7 years.

To all whom it may concern:

Be it known that I, CRAIG D. MUNSON, a citizen of the United States, residing at Wallingford, county of New Haven, State of Connecticut, have invented a new, original, and ornamental Design for a Doll or Similar Article, of which the following is a specification, reference being had to the accompanying drawing, forming a part thereof.

The figure is a front view of a doll showing my new design.

I claim:

The ornamental design for a doll or similar article substantially as shown.

CRAIG D. MUNSON.
